SPOOL STRUCTURE

William H. Bodden, York, Pa.

Application July 6, 1943, Serial No. 493,638

2 Claims. (Cl. 242—118)

This invention relates to spools of the type on which wire and insulated wire, cables, and the like are adapted to be wound.

An object of the invention is to provide an improved spool of simple and rugged construction having a minimum number of parts, all arranged and assembled together without the use of metal fastening means.

Another object of the invention is to provide an improved spool structure including a cylindrical barrel, preferably formed of a single tubular piece of heavy paper board stock, tie bars for supporting the barrel, and head structures secured to the ends of the tie bars by wedges, the tie bars, head structures, and wedges all preferably being formed of wood and held assembled together by a suitable adhesive.

Another object of the invention is to provide an improved spool structure of the above type in which the tie bars have reduced ends disposed in openings formed in the head structures, and the wedges are driven into slots formed lengthwise in each end of the tie bars, the thick ends of the wedges being greater in thickness than the width of the slots so that the wedges spread the slotted ends of the tie bars tightly into engagement with the walls of the openings in the head structures.

With the foregoing and other objects and advantages in view, the invention consists in the preferred construction and arrangement of the several parts which will be hereinafter fully described and claimed.

In the accompanying drawings:

Fig. 1 is an elevation, with parts broken away, looking at an end of a spool constructed according to the present invention;

Fig. 2 is a section taken on the line 2—2 of Fig. 1;

Fig. 3 is a detail perspective view of one of the tie bars;

Fig. 4 is a perspective view of the barrel; and

Fig. 5 is a perspective view of one of the wedges.

In order to package wire, cables, insulated wire and the like at the mills where such wire is produced, it is the custom to wind the wire, as it leaves the machines, on to spools of various sizes, depending upon the size of the wire and the amount of wire it is desired to have in each package.

Heretofore, it has been customary to construct the spools either wholly or partly of metal. With the present day restrictions on the use of metals, it has been necessary to substitute other materials in the construction of the spools, and the spool

of the present invention has been formed mostly of wood, with the barrel made from tubular paper stock of the type used for heavy mailing tubes and the like.

Referring to the drawings, the improved spool comprises two head structures 11 and 12, both of identical construction.

The heads 11 and 12 preferably are in the form of circular disks of suitable diameter, which disks are formed of wood. The disks constituting the heads may be cut either from planks or from plywood having the desired number of plies to provide a rigid, non-warping structure.

At the center of each head 11, 12, there is formed a relatively large opening 13, which opening is adapted to provide means whereby the spool can be mounted on a spindle or other supporting element (not shown).

Concentric with the center of the openings 13, each head 11, 12, is also formed with a plurality of openings 14. Any number of openings 14 may be formed in each head, and these openings should preferably be spaced equidistantly apart. In the present instance, each head 11, 12, is shown as being formed with four openings 14. However, it will be understood that either a lesser number or a greater number of these openings can be provided. The centers of the openings 14 are disposed radially from the center of the opening 13 a suitable distance, for the purpose to be hereinafter referred to, and located at any convenient point in each head 11, 12, and disposed at a greater distance outwardly from the openings 13 than is the position of the openings 14, are openings 15, through which ends of the wire wound on the spool are adapted to be inserted, in well known manner.

In order to retain the heads 11, 12, in suitable spaced relation to each other, a plurality of tie bars 16 is employed.

Each tie bar 16 is preferably formed from round wooden bars, of suitable diameter. The diameter of the main body portion of each tie bar is somewhat greater than the diameter of the openings 14, and at each end each tie bar is formed with a reduced portion 17. These reduced portions 17 have a diameter equal substantially to the diameter of the openings 14 so that the portions 17 of the tie bars can be inserted in the openings 14 of the heads 11, 12.

The length of each reduced portion 17 is equal substantially to the thickness of each head 11, 12, and a shoulder 18 is formed at the inner end of each reduced portion 17. When the parts are assembled, as shown in Fig. 2, the inner faces of

the heads 11, 12, bear against the shoulders 18 of the several tie bars.

Formed lengthwise in each end of each tie bar is a slot 19. As shown in Figs. 2 and 3, each slot 19 has a length equal substantially to twice the length of the reduced portion 17, so that the inner end of the slot terminates in the main body of the tie bar at a suitable distance from the outer end thereof. The transverse width of each slot 19 is relatively wide, so that a wedge 20 can be driven into the slotted end of each tie bar without splitting the same.

Each wedge 20 has a width equal substantially to the width of the reduced end portion 17 of each tie bar and a thick end 21 and sloping to a thin edge 22 at the other end, the thickness of the thick end 21 of said wedge being greater than the width of the slot 19 so that the wedge spreads the slotted end 17 of each tie bar 16 tightly into engagement with the wall of the opening 14 in the head.

Surrounding the several tie bars 16 and interposed between the heads 11, 12, is a cylindrical or tubular member 23, in the form of a barrel.

The cylinder 23 is preferably formed of a single piece or section of tubular paper stock of substantial heavy construction, such as the heavy paper tubes in common use for mailing purposes.

The length of the cylinder 23 is equal substantially to the distance between the shoulders 18 of each tie bar 16 so that when the parts are assembled in the manner shown in Fig. 2, the ends of the cylinder will bear tightly against the opposed inner faces of the two heads 11, 12, respectively.

As shown in Fig. 1, the tie bars 16 are so disposed in the heads 11, 12, that the several tie bars bear against the interior wall of the cylinder 23 and firmly retain the same in position without lateral shifting with respect to the tie bars.

When the parts are being assembled, suitable adhesive may be applied to the abutting surfaces of the tie bars, heads, and wedges, and also a suitable filler can be inserted in the slots 19, as indicated at 24, Fig. 2, so as to fill the cavities between the wedges and the slotted portions of

the tie bars. In this way the parts will be securely united into a rigid structure capable of withstanding shocks and hard usage.

Having thus described my invention, what I claim is:

1. A spool structure comprising a plurality of tie bars having reduced ends forming shoulders, head structures having openings formed therein for receiving the reduced ends of said tie bars, a slot formed lengthwise in each end of each tie bar, each said slot having a length equal substantially to twice the length of the reduced end of the tie bar, and a wedge driven into the slotted end of each tie bar to secure the tie bars to said head structures, each wedge having a width equal substantially to the width of the reduced tie bar end and a thickened end and sloping to a thin edge at the other end, the thickness of the thick end of said wedge being greater than the width of said tie bar slot so that the wedge spreads the slotted end of each tie bar tightly into engagement with the wall of each head structure opening.

2. A spool structure comprising a cylindrical barrel formed of a single tubular piece of substantial heavy paper stock, tie bars engaging the inner peripheral wall of said barrel at equidistant spaced points to support the barrel, each said tie bar having reduced ends forming shoulders, head structures having openings formed therein for receiving the reduced ends of said tie bars, a slot formed lengthwise in each end of each tie bar, each slot having a length equal substantially to twice the length of the reduced end of the tie bar, and a wedge driven into the slotted end of each tie bar, each wedge having a width equal substantially to the width of the reduced tie bar end and a thick end and sloping to a thin edge at the other end, the thickness of the thick end of said wedge being greater than the width of said tie bar slot so that the wedges spread the slotted ends of the tie bars tightly into engagement with the walls of the head structure openings to thereby secure the tie bars to said head structures.

WILLIAM H. BODDEN.
